[57] CLAIM

The ornamental design for a vehicle tire, substantially
as shown and described.

DESCRIPTION

FIG. 1 is a perspective view of a vehicle tire showing
our new design, it being understood that the tread pattern
is repeated throughout the circumference of the tire;

FIG. 2 is a front elevational view thereof;

FIG. 3 is a side elevational view thereof;

FIG. 4 is an enlarged fragmentary plan view thereof;
and

FIG. 5 is an enlarged sectional view thereof taken
along the line 5—5 in FIG. 4.

FIG. 1

FIG. 2

FIG. 3

FIG. 4**FIG. 5**
